DISPENSING DEVICE

Pete W. Cunningham, Los Angeles, Calif.

Application September 22, 1941, Serial No. 411,819

5. Claims. (Cl. 31—20)

This invention is a slicing and dispensing device; and since certain features of the invention are particularly applicable for slicing and dispensing thermo-plastic material such as butter, the invention is illustrated and described as a butter cutter and dispenser.

It is an object of the invention to heat the cutting element of the device for sharply defined slicing of thermo-plastic material such as butter; and more particularly to electrically heat the cutting element, with the electrical circuit automatically closed at the start of each cycle of operation and then automatically broken at the end of each cycle.

It is another object of the invention to firmly hold the material during the slicing operation; and more particularly to provide cyclic operation whereby the material is shifted forwardly while the holding means is released, and the holding means is then automatically actuated during the slicing operation, and is then automatically released at the end of each cycle of operation.

It is another object of the invention to automatically open and then reclose the dispensing device during each cycle of operation; and more particularly to automatically retain the closure means in open position when the last slice of material has been dispensed, and then automatically reclose the same responsive to recharging the dispensing device.

Further objects of the invention will be readily understood from the following description of the accompanying drawings, in which:

Fig. 1 is a side elevation of the dispensing device with its outer casing partly broken away and showing start of a cycle of operation.

Fig. 2 is a plan view of the dispensing device with its outer casing partly broken away.

Figs. 3 and 4 are fragmentary longitudinal sections through the dispensing device respectively showing start and midway of a cycle of operation.

Fig. 5 is a front elevation of the dispensing device with its outer casing partly broken away.

Figs. 6, 7 and 8 are transverse sections on the lines 6—6, 7—7 and 8—8 respectively of Fig. 3.

Fig. 9 is a wiring diagram.

The dispensing device comprises a butter receptacle and its associated slicing and dispensing mechanism, mounted in an outer casing 1. A transverse partition 2 divides the outer casing into a forward refrigerating compartment 3 which surrounds the butter receptacle, and a rear compartment 4 which contains the actuating mechanism. A hinged closure 5 at the front of the casing 1 provides for insertion and removal of

the butter receptacle, and an opening 6 in the closure 5 alines with a dispensing channel of the butter receptacle and has a hinged closure 7 which is automatically opened and then reclosed during each cycle of operation.

The butter receptacle comprises a base 10 and upstanding side walls 12. The base is slidably mounted in guideways 11 of the compartment 3, and the side walls 12 define a channel for an elongate slab of butter. The slab of butter is moved forward at the start of each cycle of operation, for projection beyond the open front of the butter-receiving channel, ready to have a slice of butter cut off.

As an instance, a follower 13 is slideable in the butter-receiving channel below guide rails 14 on the side walls 12, and is actuated step-by-step by a pawl and ratchet 15—16. The ratchet is a series of teeth along a bar 17 which is suspended from links 18 so that it extends along the butter-receiving channel above the follower 13. The links are fixed to shafts 19, which are journaled in the side walls 12 in spaced relation along the butter-receiving channel; and a spring 20 yieldably retracts the link-suspended ratchet bar. The pawl 15 is mounted on the follower 13 and projects above the same and is yieldably projected to operative position as shown at 21. The pawl and ratchet is medially of the width of the butter-receiving channel and its cooperating follower 13, so that the follower is projected step-by-step without tendency to twist and bind the follower in the butter-receiving channel.

A cutter 22 is supported by levers 23 which are pivoted to the side walls 12; and arms 24 project upwardly from the rear ends of the levers for swinging the same so as to move the cutter downwardly across the open forward end of the butter-receiving channel. This swinging movement of the levers also shifts the ratchet bar 17 against the tension of its spring 20. For this purpose, cam arms 25 are fixed to the front shaft 19 and are engaged by rollers 26 on the levers 23. The cam arms include cam surfaces 25a—25b, the surfaces 25a being arranged so that responsive to engagement by the rollers 26 the link-suspended ratchet bar 17 is shifted relative to the pawl 15, and the surfaces 25b being arranged so that throughout their engagement by the rollers 26 the ratchet bar 17 is retained in the position to which it has been shifted.

Between cycles of operation (Figs. 1 and 3) the levers 23 are in upwardly swung position so that the cutter 22 is spaced above the slab of butter 55 in the dispensing device, and the rollers 26 are

in engagement with that portion of the cam arms 25 which permits the spring 20 to shift the link-suspended ratchet bar 17 upwardly and rearwardly clear of the pawl 15. During each cycle of operation initial forward rocking of the arms 24 (for downwardly swinging the levers 23) moves the cutter 22 downwardly to position just above the slab of butter, and the rollers 26 are moved along the cam surfaces 25a so as to rock the shaft 19 from which the cam arms 25 are suspended, thereby swinging the link-suspended ratchet bar 17 downwardly and forwardly against the tension of its spring 20. As shown at Fig. 4, one of the teeth 16 thus engages the pawl 15 and moves the follower 13 forward, the distance of one slice of butter.

The slab of butter is thus projected beyond the open forward end of the butter-receiving channel, and during continued forward rocking of the arms 24 (for continuing downward swing of the levers 23) the rollers 26 are moved along the cam surfaces 25b so that the link-suspended ratchet bar 17 remains in the position to which it has been shifted (thereby retaining the follower 13 and the slab of butter in forwardly projected position), and the cutter 22 is moved downwardly through the forwardly projected slab of butter for cutting off a slice. As shown at Fig. 6 the portion of the cutter which extends across the butter-receiving channel is downwardly offset relative to the levers 23, so that at terminal downstroke of the levers the cutter is below the butter-supporting surface of the base 10. The slice of butter which has been cut off is thus free for discharge via the opening 6, the closure 7 having been automatically opened as hereafter described.

The arms 24 are then reversely rocked (for reversely swinging the levers 23 to their original position) so as to complete the cycle of operation. During initial reverse swinging of the levers the cutter 22 is moved to position just above the slab of butter, and the rollers 26 move along the cam surfaces 25b so that the ratchet bar 17 is retained in the position to which it has been shifted. During terminal reverse swinging of the levers 23 the cutter 22 is elevated to its original position spaced above the slab of butter, and movement of the rollers 26 along the cam surfaces 25a permits the spring 20 to swing the ratchet bar 17 upwardly and rearwardly. During this retractive movement of the ratchet bar the pawl 15 yields so that the follower 13 remains in the position to which it has been projected; and the parts are thus in position for repeating the cycle of operation, i. e., for engaging the pawl 15 by the next forward tooth of the ratchet bar 17, for again projecting the follower 13 and cutting off the next slice of butter.

During each cycle of operation, the slab of butter is initially free for projection by the follower 13, and is then held in projected position while the cutter 22 cuts off a slice, and is then released preparatory to repeating the cycle of operation. The holding means preferably provides a spring-urged clamping engagement.

As an instance, a holder 29 is pivoted between the side rails 14, at their forward ends and just in rear of the path of the cutter 22. A link 30 has a lost-motion connection 31 with the holder, with a spring 32 urging depression of the holder relative to the link. The link 30 is actuated by a bar 33 which is slidably mounted on the shafts 19 by means of slotted guideways 34; and the bar

33 is engaged by a cross-pin 35 which connects the arms 24 of the levers 23.

Between cycles of operation the bar 33 is retracted by the rearwardly rocked arms 24 (Figs. 1 and 3), thereby elevating the holder 29 clear of the slab of butter in the dispensing device. During initial forward rocking of the arms 24 (for forwardly projecting the follower 13), the bar 33 is shifted so as to depress the holder 29; and by the time the follower 13 has completed its forward projection the holder is in position for contact with the upper surface of the slab of butter. During continued forward rocking of the arms 24 (for cutting off a slice of butter), the lost-motion connection 31 permits floating of the holder 29, with its spring 32 yieldably urging depression of the holder so as to clamp the slab of butter against the base 10 and thus hold the same during the cutting operation (Fig. 4). During return stroke of the arms 24 (for completing the cycle of operation), the bar 33 is retracted so that the link 30 elevates the holder clear of the slab of butter (Fig. 3), ready for repeating the cycle of operation.

The cutter 22 is heated to insure a clean cut. For this purpose an electrical circuit is completed through the cutter for heating the same. The circuit is preferably automatically closed during each cycle of operation, and automatically broken when the dispensing device is not in operation.

As an instance, the ends of the cutter are electrically connected to conductor bars 35a, which extend along the levers 23 and are electrically insulated from one another; and adjacent the pivoted ends of the levers the conductor bars are electrically connected to contacts 36, which are mounted on the base 10 and are electrically insulated from one another. The connections between the bars 35a and the contacts 36 are shown as wires 37, which permit the necessary play for swinging movement of the levers 23 relative to the stationary contacts 36. When the butter dispensing device is inserted in the casing 1 the contacts 36 engage cooperating spring-projected contacts 38, which are mounted in the partition 2 and are electrically insulated from one another; and the contacts 38 are in circuit with switch mechanism (hereafter described), which closes an electrical circuit for the cutter, but only while the dispensing device is in operation.

The actuating mechanism for rocking the arms 24 is shown as a rod 40, adapted for reciprocation in the partition 2. A yoke 41 is swiveled on the rod and is yieldably spring-projected as shown at 42, to position adapted to engage a cross-pin 43 which connects the upper ends of the arms 24. A shaft 44 is manually actuated as shown at 45 and has a transversely projecting finger 46. When the dispensing device is to be inserted in the casing 1, the shaft 44 is manually rocked so that its finger 46 swings the yoke 41 against the tension of its spring 42, thereby permitting insertion of the dispensing device ready for operation, with its arms 24 retracted to their limit of movement.

As shown at Fig. 5, the shaft 44 is then manually rocked so as to disengage its finger from the yoke 41, which is thus spring-projected so as to straddle the cross-pin 43. Reciprocation of the rod 40 then rocks the arms 24 for causing the cyclic operation previously described; and when the dispensing device is to be removed from the casing 1 for cleaning, etc., the shaft 44 is again manually rocked so as to disengage the yoke 41 from the cross-pin 43.

The means for reciprocating the rod 40 is shown in the present instance as an electrical actuating mechanism. For example, an electric motor 48 is mounted in the compartment 4 and has a crank connection 49 with the rod 40 for reciprocating the latter. Suitable gearing (not shown) is provided in the housing of the motor 48, for reducing the speed of the crank 49 and preventing it continuing to rotate by its inertia after the circuit for the motor has been broken. A manual control 50, accessible from the front of the casing 1, preferably controls operation of the motor 48 and also controls the electrical heating circuit for the cutter 22. The control is preferably arranged so that manual actuation inaugurates the cycle of operation, which then continues to completion and then automatically stops, whether or not the manual control has been released.

As an instance, the electrical circuit (Fig. 9) includes parallel circuits 80—81 which are in series with parallel circuits 82—83. Switches 51 and 52 are provided between the main circuit and the respective ends of the parallel circuits 80—81, and the motor 48 and the electrically resistant cutter 22 are in the parallel circuits 82—83 respectively. Each of the switches 51—52 has an actuating lever, shown at 51a—52a, which are normally spring retracted to neutral position; and successive cyclic movements of each switch lever alternately engages the contact blade of its switch with one and then the other of the parallel circuits 80—81. In other words, swinging either switch lever from neutral position snaps its contact blade to one of its contact positions, and the blade then remains in this contact position while the switch lever returns to neutral position; and the next swinging movement of the switch lever snaps its contact blade to its other contact position, where it remains while the switch lever returns to neutral position.

The switch lever 52a is shifted by the crank connection 49, so that preparatory to each cycle of operation it will have been swung from its neutral position, thereby snapping its switch blade to one or the other of its contact positions. Midway of each cycle of operation the cyclic movement of the crank connection will have permitted the switch lever to return to neutral position (as shown by broken lines at Fig. 2), and at the end of each cycle of operation the crank connection will have again swung the switch lever from its neutral position, thereby snapping its switch blade to its other contact position.

The switch lever 51a is connected to the manual control 50 by linkage 53. When the control is manually actuated the switch lever is thus swung from its neutral position, thereby snapping its switch blade to one or the other of its contact positions. As soon as the manual control is released the switch lever is spring retracted to neutral position, and when the control is next manually actuated the switch lever is again swung from its neutral position, thereby snapping its switch blade to its other contact position.

Preparatory to each cycle of operation, the blade of switch 51 will be making contact with one of the parallel circuits 80—81, and the blade of switch 52 will be making contact with the other of said circuits. The main circuit is thus broken so that the motor 48 and the heating circuit for the cutter 22 are deenergized. To cause a cycle of operation, the control 50 is manually actuated, thereby causing the switch 51 to snap

over to its other contact and thus closing the main circuit via one or the other of the parallel circuits 80—81. The motor 48 and the heating circuit for the cutter 22 are thus energized, so that the butter cutting and dispensing device operates as previously described. At the end of the cycle of operation, the crank connection 49 causes the switch 52 to snap over to its other contact, thereby breaking the main circuit and thus deenergizing the motor 48 and the heating circuit for the cutter 22. Operation of the device thus stops, ready for repeating the cyclic operation whenever the manual control 50 is again actuated.

15 The door 7 for the opening 6 is mounted on a spring hinge 55 which tends to swing the door downwardly to closed position; and the door is controlled by a lever 56. This lever is pivoted on the closure 5 and has arms 56a projecting into the path of rollers 57 which are mounted on the levers 23. The door 7 is closed between cycles of operation, with the arms 56a below the rollers 57 (Figs. 1 and 3). During downward swing of the levers 23 (for forwardly projecting the slab of butter and cutting off a slice) the rollers 57 engage the arms 56a and swing the door 7 to open position (Fig. 4) for discharging the slice of butter; and during return swing of the levers 23 (for completing the cycle of operation) the rollers 57 permit return swing of the arms 56a so that the door 7 is spring-retumed to closed position.

20 During that cycle of operation which discharges the last slice of the slab of butter, the door 7 is swung open as above described, but instead of then returning to closed position it is automatically retained in open position. A new slab of butter may thus be inserted, thereby automatically releasing the door-retaining means so that the door is spring-retumed to closed position, ready for slicing and dispensing the new slab of butter.

25 As an instance, one of the arms 56a is laterally offset and then reversely bent at its end, and terminates in a roller 58 which is clear of the path of the roller 57; and a catch 59 is mounted on the closure 5 and is shiftable into or out of the path of travel of the roller 58. The catch is actuated by a link 60, which is engaged by the forward end of a bar 61 which extends along one of the side walls 12 and is pivoted thereto as shown at 62. A lever 63 is pivoted to this side wall, and has a roller 64a at its upper end engaging the underside of the bar 61. The lever 63 is shifted by a bar 64 which slides on one of the guide rails 14 and which has abutment pins 65—66 projecting from its front and rear ends respectively. A finger 67 projects upwardly from the follower 13 and cooperates with the pins 65—66 for shifting the bar 64 so as to swing the lever 63.

30 When a slab of butter is inserted in the dispensing device it retracts the follower 13 to its rear limit of movement, thereby engaging the pin 66 by the finger 67 and thus retracting the bar 64. As shown at Fig. 4, this movement of the bar 64 shifts the lever 63 so that its roller 64a engages a surface 70 of the bar 61, thereby elevating and retaining the bar in elevated position, and thus elevating the link 60 against the tension of a spring 71 so as to depress the catch 59 to inoperative position, clear of the path of travel of the roller 58. The parts remain in this position during successive cyclic operations of the dispensing device, so that the catch 59 is re-

tained in inoperative position and the door 7 is opened and then recloses during each cycle of operation, as previously described.

At the start of that cycle of operation which forwardly projects the follower 13 so as to dispense the last slice of a slab of butter, the forward end of the finger 67 engages the pin 65 and thus shifts the bar 64 forwardly on its rail 14. This swings the lever 63 so that its roller 64a alines with a depression 72 in the bar 61, and the bar 61 and the link 60 are thus depressed by the spring 71, so that the catch 59 is shifted to operative position in the path of travel of the roller 58. When the door 7 is swung open (during the cycle of operation which dispenses the last slice of a slab of butter) the roller 58 thus engages and depresses the catch 59 against the tension of its spring 71, so that the roller may move past the catch to position in which the door 7 is at its limit of opening movement, and the spring 71 then returns the catch to operative position (Fig. 4) so as to form an abutment for engagement by the roller 58, for preventing reclosing of the door 7.

A new slab of butter may thus be readily inserted in the dispensing device, thereby retracting the follower 13 so that its finger 67 engages the pin 66 for again elevating the bar 61 and thus depressing the catch 59 to inoperative position. The roller 58 is thus released, so that the door 7 is spring-returned to closed position, ready for step-by-step slicing and dispensing of the new slab of butter.

I claim:

1. In a dispensing device, a receptacle having an outlet and adapted for reception of thermoplastic material, a follower for projecting the material step-by-step beyond the outlet during each cycle of operation, a cutter for slicing a projecting portion of the material during each cycle of operation, the cutter being of electrical resistant material and included in an electrical circuit for heating the cutter, means included in an electrical circuit for causing cyclic operation of the follower and cutter, and a control for closing the electrical circuits for inaugurating each cycle of operation and heating the cutter, and for automatically opening the electrical circuits for ter-

minating each cycle of operation and discontinuing heating of the cutter.

2. In a dispensing device, a receptacle having an outlet, means for projecting material step-by-step beyond the outlet, a cutter for slicing a projecting portion of the material, means for clamping the material in the receptacle, means for successively actuating the projecting means and the cutter, and a connection operated by the actuating means for releasing the clamping means during projection of the material and actuating the clamping means while the material is projected and during operation of the cutter.
3. In a dispensing device, a receptacle having an outlet, means for projecting material step-by-step beyond the outlet, a cutter for slicing a projecting portion of the material, means for clamping the material in the receptacle, means for successively actuating the projecting means and the cutter, and a lost-motion spring-urged connection operated by the actuating means for releasing the clamping means during projection of the material and yieldably urging clamping engagement during operation of the cutter.
4. In a dispensing device, a receptacle having an outlet, means for projecting material step-by-step beyond the outlet, a cutter for slicing a projecting portion of the material, a closure for the outlet, means for opening and then permitting reclosing the closure during each of successive step-by-step projections and slicing of material, and means actuated responsive to projection of the last portion of the material for retaining the closure in open position.
5. In a dispensing device, a receptacle having an outlet, means for projecting material step-by-step beyond the outlet, a cutter for slicing a projecting portion of the material, a closure for the outlet, means for opening and then permitting reclosing the closure during each of the successive step-by-step projections and slicing of material, means actuated responsive to projection of the last portion of the material for retaining the closure in open position, and means actuated responsive to resupplying the receptacle with material for releasing the retaining means so as to permit reclosing of the closure.

PETE W. CUNNINGHAM.
